UNITED STATES PATENT OFFICE.

GEORGE BECK, OF ST. LOUIS, MISSOURI.

HARNESS ATTACHMENT.

SPECIFICATION forming part of Letters Patent No. 540,014, dated May 28, 1895.

Application filed March 29, 1895. Serial No. 543,680. (No model.)

To all whom it may concern:

Be it known that I, GEORGE BECK, a citizen of the United States, residing at St. Louis, in the State of Missouri, have invented certain new and useful Improvements in Harness Attachments; and I do hereby declare that the following is a full, clear, and exact description of the same, reference being had to the annexed drawings, making a part of this specification, and to the letters of reference marked thereon.

The present invention has relation to that class of harness attachments for which a patent was granted to me November 13, 1894, No. 529,014, and is designed as an improvement thereon, which improvement consists in the several details of construction substantially as shown in the drawings and hereinafter described and claimed.

Figure 1 of the drawings represents a perspective view of my improved attachment, showing the casing partly broken away at one corner thereof; Fig. 2, a longitudinal section taken through the casing; Fig. 3, a horizontal section taken on line $\alpha\alpha$ of Fig. 2.

In the accompanying drawings A represents closely coiled springs connected at their ends to grooved pins a , the grooves thereon forming seats for the coils of the springs to hold them securely thereto as shown in my former patent. These grooved pins project from hangers B C at the respective ends of the attachment as shown in Fig. 2 of the drawings, the hangers B extending outside the end of the casing D and connected by a transverse bolt b by which a loop is formed for attaching thereto a suitable leather strap to which the shaft-tug is buckled or otherwise secured.

The hangers C are connected to the opposite end of the casing by means of the transverse bolt c , which bolt extends through the sides of the casing and through ears d upon the under side of a cap-plate E and also through the hangers. This cap-plate E has projecting flanges e upon its four sides which flanges overlap the edges of the casing D and form a close and neat connection between the two.

The cap-plate E closes the opening at the end of the casing D and gives a neat appear-

ance thereto, and as the casing is constructed of leather the cap-plate forms a means of strengthening the casing at its end while the ears d which project into the casing prevent the sides thereof from collapsing and holds them rigid. This cap-plate E upon its outer side has a central lug f to which is pivoted a clevis F having a slot g for convenience of attaching thereto the saddle of the harness. This clevis is pivotally connected to the lug h of the cap-plate by means of a screw-bolt h which extends through holes in the sides of the clevis and through a hole in the lug, a screw nut engaging the screw threaded end of the bolt whereby said clevis may be removed when it is desired to attach the saddle thereto. The saddle is attached to the clevis by slipping the latter through the usual ring or loop at the upper part of the saddle of harness and afterward replacing the clevis by connecting it to the lug on the cap-plate, or in case of a buckle being used on the harness, the clevis is slipped through the loop thereof and the tongue of the buckle extending through the slot g . The clevis being pivotally connected to the lug upon the cap-plate allows the attachment to swing back and forth to adapt itself to the motion of the horse.

The meeting edges of the casing D are secured by stitching or by suitable fastenings i as shown, and the casing being formed of leather instead of metal renders the attachment comparatively noiseless.

One or more springs may be used as found most desirable and any well known means may be employed for pivotally and detachably connecting the clevis F to the lug f upon the cap-plate.

The employment of the cap-plate E with its ears d extending down into the casing D causes the weight or strain of the springs to be brought directly upon the ears and not upon the sides of the leather casing.

The attachment herein described takes the place of the tug-strap or bearer of the harness and its object is to prevent the horse from becoming sore where the saddle rests by the motion of the shafts as clearly described in my former patent.

Having now fully described my invention,

what I claim as new, and desire to secure by Letters Patent, is—

An attachment to harness, consisting of a suitable casing, one or more springs contained therein, hangers connected thereto, a flanged cap-plate having ears extending down into the casing and having a central lug upon its upper side, a slotted clevis pivotally and detachably connected to the lug, and a bolt extending transversely through the sides of the

casing, the ears, and the hangers at the upper end of the springs, substantially as and for the purpose described.

In testimony that I claim the above I have hereunto subscribed my name in the presence ¹⁵ of two witnesses.

GEORGE BECK.
